MACHINE FOR MAKING PAPER BAGS

Arno Finke, Lengerich, Westphalia, Germany

Application July 27, 1938, Serial No. 221,586
In Germany August 13, 1937

6 Claims. (Cl. 93—18)

My invention relates to a machine for making paper bags from a sheet which is formed into a tube.

In known machines of this kind, the waste end 5 which is inevitably formed between the bottom of one bag and the top of the next by producing the top and bottom flaps of the bags, is removed from the partly finished bag at the same time as, or immediately subsequent upon, the cutting of 10 the tube into bag sections, that is, as an intermediate stage in the making of the bag. Since the subsequent stages must be considered, complicated precision mechanism is required for removing the waste end, and is liable to failure, 15 especially at comparatively high operating velocity.

It is an object of my invention to improve a machine of the kind described by removing the waste end not as an intermediate, but as the final 20 stage in the making of the bags, so that it is not constrained by consideration of subsequent stages.

To this end, in a machine of the kind described, I provide means for defining a waste end for each bag on the sheet the tube is formed from. Such 25 means may be a pair of rollers which produce scores, creases, or perforations in the sheet before it is formed into the tube. I further provide means, such as a pair of feed rollers and a former plate, for forming a flat tube from the scored 30 sheet, means for finishing the bag by cutting it from the tube, folding its bottom flap, and pasting it to the body, and means for tearing the waste end off each finished bag.

In the accompanying drawings a machine embodying my invention is illustrated diagrammatically by way of example.

In the drawings

Fig. 1 is an elevation, and

Fig. 2 is a plan view of the machine.

40 Figs. 3, 4, and 5 illustrate three stages in the making of the bags

Referring now to the drawings, a sheet 1 from a roll R is continuously drawn through between a lower scoring roller 2 and an upper scoring 45 roller or sector 3 mounted to rotate between standards S, by a pair of feed rollers 6. Each feed roller is subdivided into two narrow disks near the ends of its shaft. In the upper feed roller, a squeezing roller 6' is arranged centrally 50 between the two disks. The feed rollers are mounted to rotate between frame members F above and below a former plate 4 having recesses in its sides for admitting their end disks.

The scoring rollers 2 and 3 produce scores in 55 the sheet which are here shown as rows of per-

forations by way of example but may be creases or other means for weakening the paper at predetermined points. The scores are straight lines a, a', a'', etc., extending inwardly from the edge l' in parallel and spaced relation for about one-third of the width of the sheet l, and similar lines d, d', d'', etc., extending inwardly from the other edge l'' of the sheet l. At its inner end, each score has a hook, or angular extension, b, b', b'', etc., for the scores a, etc., and c, c', c'', etc., for the scores d etc. including an angle of 45 degs. with the score.

After having been scored by the rollers 2 and 3, and gummed along its edge l'' by a device 18, the sheet l is formed into a tube about the former plate 4 by the side disks of the feed rollers 6. The gummed edge l'' is inverted, Fig. 2, and placed on the plain edge l' against which it is pressed by the squeezing roller 6'. In the folded tube, Fig. 3, the scores a'' and d'' make up a single line across the upper overlapped portion 15 of the tube, and their hooks b'' and c'' extend into the solid lower portion of the tube from both side edges.

The rear edge 8 of the former plate 4 is toothed 25 and chamfered at an angle of 45 degs. at both ends 8'. The tube moves over the toothed edge 8 under the push of the rollers 6 and is then engaged by a pair of stripping rollers 7. A cutting device is arranged between the pairs of rollers 6 30 and 7 and comprises an upper inclined and fixed blade 9 whose rear edge is toothed and arranged at a short distance ahead of the edge 8. The lower blade 10 is arranged at a short distance to the rear of the edge 8 and is secured on a shaft 35 10' which is mounted to rotate at the side of one of the frame members F.

The rotation of the lower blade 10 is so timed with respect to the feed imparted to the tube by the rollers 6, that it engages the tube from 40 below when the scores a'', d'' have moved a short distance beyond the rear edge 8 of the former blade 4. Owing to the staggering of the toothed edge 8 with respect to the toothed rear edge of the upper blade 9, the overlapped portion is cut 45 along a line e which trails with respect to the line f along which the solid portion of the tube is cut so that a bottom flap B is formed on the solid portion which projects beyond the line e. Conversely, in the bag h which is now stripped 50 by the rollers 7 rotating at higher speed than the feed rollers 6, the edge e' of the overlapped portion projects beyond the edge f' of the solid portion, and the waste end g extends from the score a'', d'' to the edge e'. The waste end g is 55

not removed at this stage but goes to the further stations with the bag *h*. It will appear that only one separation—of the bag *h* and its waste end *g* at *e*, *e'* and at *f*, *f'*—is performed while the bag is being made. The second separation—tearing the waste end *g* off the bag *h*—is performed after the bag has been finished, as will now be described.

The stripping rollers deliver the partly finished bag *h* to a pair of rollers 11, 12. The lower roller 11 is equipped with means 19 for engaging the bag *h* at its leading end where the bottom flap *B* is positioned, and the upper roller 12 is supplied with paste by a gummer 20. The paste is applied to the overlapping portion at the point against which the bottom flap is pressed, by a pasting strip 13 on the upper roller. An intermediate roller 21 presses the flap *B* against the gummed portion, and the bag, with the waste end *g* still adhering to it, but otherwise finished, is delivered to a tear-off device.

This device comprises a supporting roller 14 on a shaft 22, a retaining roller 15, and a tear-off roller 16. The supporting roller 14 comprises a set of disks arranged in spaced relation and alternately fast and loose on its shaft 22. The tear-off roller 16 comprises a sector supported by two sleeves 30 on a shaft 26, and recessed opposite the fast disks 14 and equipped with points 23 extending into the spaces between the disks. A spur gear 27 on the shaft 22 and a spur gear 28 on the shaft 29 of the retaining roller 15 rotate this roller at a peripheral velocity which is less than that of 14 and 16.

The bag *h* is delivered to the supporting roller 14 which rotates clockwise, as indicated by the arrow in Fig. 1, and is first engaged by the tear-off roller 16 and moved into the position illustrated, without being interfered with by the points 23 of the anti-clockwise rotating retaining roller 15 for the present, but when the bag has arrived in the said illustrated position, the points 23 have advanced so far as to penetrate the waste end *g*. The bag is now gripped between the sector of the tear-off roller 16 and the fast disks of the supporting roller 14 by which it is moved toward the delivery end of the machine at the peripheral velocity of both members while the waste end *g* is retained by the more slowly rotating roller 15. While the waste end *g* is thus retained by the pins 23 the bag *h* moves on until the paper is torn along the perforations *a''*, *d''* and the bag, with its top flap *T*, is ejected while the waste end *g*, upon further rotation of the retaining roller 15, is deposited in a box 17.

The superiority of this method over the known method in which the tearing off of the waste end is an intermediate stage of the manufacture, will now be realized. In the known method, the waste end must obviously be separated along two lines, viz. its connection to the tube, and its connection to the partly finished bag. As mentioned, this requires complicated mechanisms operating with great precision, as obviously the length of the waste end should be a minimum, and the mechanism may easily get out of order on account of its complication. While in the known method the severing of the waste end and the bag and the tube necessitates two operations performed with maximum precision, only a single

severing operation is performed in my machine as the intermediate stage. This severing occurs along the lines *e* and *f*, Figs. 3 and 4, while the connection between the bag and the waste end is not broken along the line of perforations *a''*, *d''*. This operation is performed by quite simple means, viz. the toothed rear end of the former plate 4, the toothed rear end of the upper blade 19, and the lower blade 10, and it is not necessary to provide complicated means for the exact location of two distinct operations, as in the old method. Nor is the severing operation influenced by the velocity of operation. The final stage, the tearing-off of the waste end *g* along *a''*, *d''*, is performed at a point where it is independent of the intermediate stage, and again by very simple means.

My novel machine therefore is more simple and more reliable than the known machines, and is suitable for high-speed operation.

Another important improvement achieved by my machine resides in the fact that the scores, or lines of perforations, do not extend all over the width of the sheet, as they do in the known machines. As described, the scores are substantially restricted to the overlapped portion of the tube, and only the hooks at the ends of the scores extend into the solid portion. Obviously, the inevitable weakening of the cross-section by the scores is reduced to a minimum in my machine, which is important for high-speed operations, since in such cases a considerable pull is exerted on the sheet and the paper tube by the feeding means, so that the stress becomes excessive in a much weakened section, especially when the sheet is formed over the former plate.

The favorable features of my machine permit of extraordinarily high speeds of operation.

While the tear-off device 14, 15, 16 has been described as adapted to a machine for making paper bags, it is understood that it has a wider field of usefulness and can be used wherever strips of paper are separated.

I claim:

1. In a machine for making paper bags from a sheet formed into a tube, means for defining a waste end for each bag on the sheet the tube is formed from, by scores extending inwardly from the side edges of the sheet for part of its width only, means for forming the scored sheet into a tube, means for finishing the bags, a supporting roller, a shaft forming part of the supporting roller, alternately fast and loose disks on the shaft, a tear-off roller arranged to engage the finished bags together with the fast disks and to rotate at a peripheral velocity equal to that of the fast disks, and a retaining roller arranged to engage the waste end of the bags together with the loose disks and to rotate at a lower peripheral velocity.

2. In a machine for making paper bags from a sheet formed into a tube, means for defining a waste end for each bag on the sheet the tube is formed from, by scores extending inwardly from the side edges of the sheet for part of its width only, means for forming the scored sheet into a tube, means for finishing the bags, a supporting roller, a shaft forming part of the supporting roller, alternately fast and loose disks on the shaft, a tear-off roller arranged to engage the finished bags together with the fast disks and to rotate at a peripheral velocity equal to that of the fast disks, a retaining roller arranged to engage the waste end of the bags together with the loose disks and to rotate at a lower peripheral velocity.

eral velocity, and pins on the retaining roller for penetrating the waste end.

3. In a machine for making paper bags from a sheet formed into a tube, means for defining a waste end for each bag on the sheet the tube is formed from, by scores extending inwardly from the side edges of the sheet for part of its width only, means for forming the scored sheet into a tube, means for finishing the bags, a supporting roller, a shaft forming part of the supporting roller, alternately fast and loose disks seated on the shaft in spaced relation, a tear-off roller arranged to engage the finished bags together with the fast disks and to rotate at a peripheral speed equal to that of the fast disks, a retaining roller arranged to engage the waste end of the bags together with the loose disks and to rotate at lower peripheral velocity, and pins on the retaining roller extending into the spaces between the disks, for penetrating the waste end.

4. In a machine for making paper bags from a sheet formed into a tube, means for feeding the sheet through the machine, means for defining a waste end for each bag on the sheet the tube is formed from, by scores extending inwardly from the side edges of the sheet for part of its width only, means for forming the sheet into a tube, with the side edges from which the scores extend inwardly, overlapping each other, means for severing the tube in such manner into bags that a bottom flap on the leading end of the solid side of the tube projects beyond the leading end of the overlapped side and forms the bottom flap of each bag, means for finishing the bags by folding and securing the bottom flap to the corresponding bag, and means located rearwardly of the finishing means for tearing the waste end off each finished bag.

5. In a machine for making paper bags from a sheet formed into a tube, means for feeding the sheet through the machine, means for defining a waste end for each bag on the sheet the tube is formed from, by scores extending in-

wardly from the side edges of the sheet for part of its width only, means for forming the sheet into a tube, with the side edges from which the scores extend inwardly, overlapping each other, a blade arranged opposite the overlapped side of the tube, and another blade arranged opposite the solid side of the tube at the rear of the first-mentioned blade in the feeding direction; for severing the tube in such manner into bags that a bottom flap on the leading end of the solid side of the tube projects beyond the leading end of the overlapped side and forms the bottom flap of each bag, means for finishing the bags by folding and securing the bottom flap to the corresponding bag, and means located rearwardly of the finishing means for tearing the waste end off each finished bag.

6. In a machine for making paper bags from a sheet formed into a tube, a pair of scoring rollers for defining a waste end for each bag on the sheet the tube is formed from, by scoring the sheet along lines extending inwardly from the side edges of the sheet for part of its width only, means for gumming the sheet at one of its side edges, feed rollers arranged at the rear of the scoring rollers, a former plate arranged between the feed rollers for forming the scored sheet into a tube, severing means arranged at the rear of the rear edge of the former plate, for severing the tube in such manner into bags that a bottom flap at the leading end of the solid side of the tube projects beyond the leading end of the opposite side where the gummed and plain edges of the sheet overlap, and forms the bottom flap for each bag, a pair of stripping rollers at the rear of the severing means, a pair of rollers for folding and pasting the bottom flap to the corresponding bag delivered by the stripping rollers, and means arranged at the rear of the folding and pasting rollers for tearing the waste end off each finished bag.

ARNO FINKE.
